DESIGN FOR A PROJECTOR

Lester Geis, New York, N. Y., and Charles L. Metzler, Palisades Park, N. J., assignors to American Optical Company, Southbridge, Mass., a voluntary association of Massachusetts

Application September 10, 1945, Serial No. 121,976

Term of patent 14 years

(Cl. D61—1)

To all whom it may concern:

Be it known that we, Lester Geis and Charles L. Metzler, citizens of the United States of America, residing at New York city and Palisades Park, in the counties of New York and Bergen and States of New York and New Jersey, respectively, have invented a new, original and ornamental Design for a Projector, of which the following is a specification, reference being made to the accompanying drawing forming a part thereof.

Fig. 1 is a perspective view of a projector showing our new design; and

Fig. 2 is a view thereof in side elevation.

The characteristic features of our design reside in the portions shown in full lines in the drawing.

We claim:

The ornamental design for a projector or similar article, substantially as shown and described.

LESTER GEIS.
CHARLES L. METZLER.
